UNITED STATES PATENT OFFICE

114,061

DESIGN FOR A GAME DEVICE

Patrick Fogarty, Washington, D. C.

Application January 5, 1939, Serial No. 82,174

Term of patent 3½ years

To all whom it may concern:

Be it known that I, Patrick Fogarty, a citizen of the United States, residing at Washington, in the District of Columbia, have invented a new, original, and ornamental Design for a Game Device, of which the following is a specification, reference being had to the accompanying drawing, forming a part thereof.

In the drawing:

The dominant feature of the design is shown in full lines in the drawing.

I claim:

The ornamental design for a game device, as shown and described.

PATRICK FOGARTY.
